FLOWER RECEPTACLE OR SIMILAR
ARTICLE

Chris Mueller, Jr., Burbank, Calif.

Application March 27, 1950, Serial No. 8,809

Term of patent 14 years

(Cl. D29—28)

To all whom it may concern:

Be it known that I, Chris Mueller, Jr., a citizen of the United States of America, and a resident of the city of Burbank, in the county of Los Angeles and in the State of California, have invented a new, original, and ornamental Design for a Flower Receptacle or Similar Article, of which the following is a specification, reference being had to the accompanying drawing, which drawing forms a part of this invention.

In the drawings:

Figure 1 is a top perspective view of a flower receptacle or similar article, showing my new design,

Figure 2 is a side elevational view thereof, and Figure 3 is a cross sectional view thereof.

I claim:

The ornamental design for a flower receptacle or similar article, substantially as shown.

CHRIS MUELLER, JR.
